CLAIM

The ornamental design for a strain-relieving solar cell interconnect, as shown and described.

DESCRIPTION

FIG. 1 is a front, top, right side perspective view of the strain-relieving solar cell interconnect in accordance with the present invention;

FIG. 2 is a front view, the rear view is a mirror image thereof;

FIG. 3 is a top view, the bottom view is a mirror image rear view thereof;

FIG. 4 is a right side view;

FIG. 5 is a left side view;

FIG. 6 is a front view expanded twelve times;

FIG. 7 is a right side view having segments **8A-8K** thereof delineated by dashed lines for enlargement of each segment to show details as shown in subsequent right side views of FIGS. **8A-8K** herein;

FIGS. **8A-8K** are partial enlarged views of respective segments identified as **8A-8K** shown in FIG. 7, the segments being expanded ten times to illustrate the detail thereof;

FIG. 9 is a left side view having segments **10A-10K** thereof delineated by dashed lines for enlargement of each segment to show details as shown in subsequent left side views of FIGS. **10A-10K** herein; and,

FIGS. **10A-10K** are partial views of segments **10A-10K** shown in FIG. 9, the segments being expanded ten times to illustrate the detail thereof.

The dashed and broken lines shown in FIGS. 7, **8A-8K**, **9** and **10A-10K** are for the purpose of illustrating design features and form no part of the claimed design.

1 Claim, 14 Drawing Sheets
